UNITED STATES PATENT OFFICE.

JOHN B. HADAWAY, OF BROCKTON, MASSACHUSETTS, ASSIGNOR TO UNITED SHOE MACHINERY COMPANY, OF PATERSON, NEW JERSEY, A CORPORATION OF NEW JERSEY.

STITCH-SEPARATING MACHINE.

No. 888,083.

Specification of Letters Patent.

Patented May 19, 1903.

Application filed June 2, 1905., Serial No. 263,363.

To all whom it may concern:

Be it known that I, JOHN B. HADAWAY, a citizen of the United States, residing at Brockton, in the county of Plymouth and

5 State of Massachusetts, have invented certain new and useful Improvements in Stitch-Separating Machines; and I do hereby declare the following to be a full, clear, and exact description of the invention, such as will 10 enable others skilled in the art to which it appertains to make and use the same.

The present invention relates to stitch separating machines which are used in the manufacture of shoes to indent the intervals 15 between the stitches appearing on the upper surface of the edge of the sole so as to bring the stitches into prominence and impart a finished appearance to this portion of the shoe.

Machines adapted to operate upon a finished seam to indent the intervals between the stitches are complicated in construction 20 and slow in operation as compared with machines which are adapted to form ornamental indentations in imitation of stitches upon 25 the sole edge of shoes which are not provided with an outseam or in which the stitches of the outseam are sunk in a groove or channel. In the latter class of machines an indenting wheel is usually employed provided with 30 teeth shaped and spaced to produce the desired form of indentations, this wheel being mounted so as to rotate on its axis as the work passes beneath the wheel. The use of an indenting wheel enables these machines to 35 be operated at a high rate of speed and to be constructed in an extremely simple and compact manner. It has heretofore been found to be impracticable to use such an indenting wheel for operating upon a finished seam 40 since the stitches in all boot and shoe work vary more or less in length and when it is attempted to act upon a finished seam with an indenting wheel the teeth of the wheel do not enter the stitch intervals but strike upon the 45 crowns of the stitches, mutilating the seam and injuring or spoiling the shoe.

The principal object of the present invention is to provide a stitch separating machine adapted to operate upon the stitches of a finished seam which is as simple in construction 50 and as rapid in operation as machines which have been heretofore used for forming impression or imitation stitches.

Other objects of the invention are in general to improve the construction and mode of 55 operation of stitch separating machines.

With these objects in view the present invention contemplates the provision in a stitch separating machine of a stitch separating and indenting wheel provided with a series of teeth formed and spaced to permit a relative slipping movement between the wheel and the work when the stitches vary in length to cause each tooth to locate itself in the interval between two stitches. 65

The invention also contemplates providing the wheel with a series of grooves to shape the crowns of the stitches, the grooves being so shaped and spaced with relation to the teeth as to coöperate with the teeth in permitting a relative slipping movement between the wheel and the work to cause the grooves to locate themselves upon the crowns of the stitches. 70

Rotary stitch separating and indenting 75 tools or wheels have heretofore been devised, such for instance, as are disclosed in applicant's prior patents No. 548,309, dated October 22, 1895, and No. 664,405, dated December 25, 1900. These wheels have, however, been provided with a series of radially extending stitch separating blades adapted to move with relation to each other in locating the stitch intervals. The wheel which forms the principal feature of the present invention is clearly distinguished from such 85 wheels in that the teeth of the wheel are not mounted to move independently of each other but are so formed and arranged, that the location of the teeth in the stitch intervals is produced by the relative slipping movement of the wheel and work. A wheel embodying the present invention is further distinguished therefrom in that it may be provided with grooves adapted to be located 90 upon and shape the crowns of the stitches. 95

In the embodiment of the invention herein-after described the indenting wheel is of small diameter and the number of teeth upon its periphery is small compared with the size 100 of the teeth, so that only a few teeth are in engagement with the work at one time and a relative slipping movement of the wheel and work is permitted as each stitch interval or stitch crown is acted upon. On account of 105 the small diameter of the stitch separating

and indenting wheel means in addition to that usually employed in impression or imitation stitch machines for supporting the wheel against the thrust of the work are provided. Broadly considered the invention is not limited to a construction in which these additional means are provided but the provision of these means is deemed preferable and constitutes a feature of the invention.

- 10 In its preferred form the stitch separating wheel is provided with a peripheral surface convexly curved lengthwise of the wheel in order that the teeth which project from the peripheral surface of the wheel may act to better advantage upon the stitches of the seam, and a stitch separating and indenting wheel having its peripheral surface curved in this manner constitutes a feature of the invention.
- 20 The machine hereinafter specifically described is provided with upper and lower work supports, the lower work support being adjustable to change the angle of the work engaging surface with relation to the work engaging surface of the upper work support.
- 25 In order to change the character of the indentations made by the stitch separating and indenting wheel and to adapt the machine for operation upon certain styles of work the stitch separating and indenting wheel is adjustably mounted so that its angular position with relation to the work engaging surface of the upper work support can be varied. This adjustment of the stitch
- 30 separating and indenting wheel with relation to the upper work support constitutes a feature of the present invention which is also applicable to machines provided with other forms of stitch separating and indenting
- 35 tools, or to machines adapted for making impression or imitation stitches.

Other features of the present invention consist in certain devices, combinations and arrangements of parts hereinafter described and claimed, the advantages of which will be obvious to those skilled in the art from the following description.

The preferred form of the present invention is illustrated in the accompanying drawings in which

Figure 1 is a view in side elevation of a stitch separating and indenting machine embodying the same; Fig. 2 is a view in front elevation illustrating the manner in which the stitch separating and indenting wheel is mounted; Fig. 3 is a view in side elevation partly in section of the parts illustrated in Fig. 2; Fig. 4 is a detail view showing a portion of a shoe in cross section and the stitch separating and indenting wheel in position to act upon the stitches of the outseam and Figs. 5 and 6 are diagrammatic views illustrating the action of the indenting wheel in separating the stitches and in indenting the

stitch intervals and shaping the crowns of the stitches.

The machine illustrated in the drawings to which the present invention has been applied is similar in the construction, arrangement and mode of operation of many of its parts to an impression or imitation stitch machine disclosed in an application filed by the present applicant of even date herewith, but it is to be understood that the invention is not limited to this machine but is capable of being embodied in many different kinds of machines and may be applied to many of the stitch separating machines and to many of the imitation or impression stitch machines which have heretofore been devised.

The machine illustrated in the drawings is provided with a yieldingly mounted lower work support, with an adjustable upper work support, with a spring pressed lever upon which the stitch separating and indenting wheel is mounted and by which the wheel is kept constantly in engagement with the work, and with a vibratory hammer lever which acts to deliver a series of blows in rapid succession upon the wheel carrying lever thereby causing the stitch separating and indenting wheel to deliver a series of blows upon the work. These parts are constructed and arranged in the manner disclosed in the application above referred to but since they are illustrated in the drawings accompanying this application they will be briefly described herein.

Referring to the drawings, 1 indicates the lower work support which is frusto conical in shape and is mounted to rotate on a stud projecting from a block 2. The block 2 is pivotally mounted at 3 upon the upper end of a vertical slide 4 and is provided with an arc shaped slot 5 through which a securing bolt 6 passes whereby the block 2 can be adjusted to change the angular position of the work engaging surface of the lower work support with relation to the adjacent surfaces of the upper work support and the separating and indenting wheel. The slide 4 is yieldingly supported by means of a spring 7 coiled around a rod 8 which projects downwardly from the slide through an adjusting sleeve 9, and is provided below the sleeve with an adjustable stop nut 10, by means of which the upward movement of the slide and the work support is limited when no work is in the machine. A treadle (not shown) is connected to the lower end of the rod 8 by means of which the slide and work support may be depressed by the operator.

The lever which carries the stitch separating and indenting wheel is indicated at 11 and is pivotally mounted upon a shaft 12. The lever moves freely upon its pivot and is acted upon by a coiled spring 13 which is connected to an arm 14 projecting below the

pivot of the lever. By means of this spring the upper end of the lever 11 is pressed towards the lower work support and the stitch separating and indenting wheel is held 5 yieldingly in contact with the work. A stop pin 15 is arranged to engage the arm 14 of the lever 11 and limit the downward movement of the stitch separating and indenting wheel when no work is in the machine.

10 The vibrating hammer lever for actuating the lever 11 to cause the stitch separating and indenting wheel to deliver a series of blows in rapid succession upon the work is indicated at 16. This lever is pivotally 15 mounted upon the shaft 12 by means of two arms which extend upon opposite sides of the lever 11. At its upper end the lever 16 is provided with an adjustable block 17 which is arranged to contact with the block 18 upon 20 the upper end of the lever 11. A rapid vibrating movement is imparted to the lever 16 by means of a cam 19 upon the driving shaft 20, which cam engages blocks 21 mounted in the forked rear end of the lever. The stop 25 pin 15 is so arranged that when no work is in the machine the block 18 is out of the path of movement of the block 17 so that when no work is in the machine the stitch separating and indenting wheel remains stationary. 30 When work is inserted in the machine the lever 11 is moved to bring the block 18 into the path of movement of the block 17.

The upper work support is indicated at 22 and is secured to a block 23 so as to be capable of an inward and outward adjustment. The block 23 is secured to the frame of the machine so as to be capable of a vertical adjustment and by means of these two adjustments the upper work support may be 40 brought into the desired position with relation to the stitch separating and indenting wheel and to the lower work support. This upper work support is substantially the same as the guide of the machine disclosed in the 45 application hereinbefore referred to but is preferably adjusted so as to bear upon the surface of the work which is acted upon by the stitch separating and indenting wheel.

Referring now to the constructions illustrated in the drawings which embody the several features of the present invention, 24 indicates the stitch separating and indenting wheel which as shown is of small diameter as compared with the size of teeth upon its periphery. The shape and arrangement of the teeth and grooves of the wheel and the manner in which the wheel acts to locate the teeth in the stitch intervals and the grooves upon the crowns of the stitches will be clearly 55 understood from an inspection of Figs. 5 and 6. In these figures 25 indicates the work, 26 the stitches of the seam which have not been 60 acted upon by the wheel, 27 a stitch, the crown of which has been completely shaped

and the stitch interval at each side completely indented, 28 a stitch which is being acted upon by the wheel in Fig. 5 and which has been completed in Fig. 6, and 29 a stitch which is being acted upon by the wheel in both figures. At the stage of the operation indicated in Fig. 5 it will be noted that the tooth 30 of the wheel has freed itself from the indentation between the stitches 27 and 28, that the tooth 31 is acting upon the interval between the stitches 28 and 29 and that all 70 the other teeth of the wheel are above the surface of the work. The tooth 31 is the only tooth which is firmly in engagement with the work and, consequently, a relative slipping movement of the wheel and work is 75 permitted to allow the tooth to locate itself in the interval between the stitches 28 and 29 in case the stitches are longer or shorter than the average.

In Fig. 6 the wheel is represented as having 85 rotated to bring the tooth 31 into a vertical position and to bring the tooth 32 into engagement with the work. At this stage of the operation the groove between teeth 30 and 31 is out of engagement with the stitch 90 28, the stitch 29 is in engagement with the groove between teeth 31 and 32 and the stitch 26 adjacent to the stitch 29 is out of engagement with the groove between the tooth 32 and the tooth 33. The groove between the teeth 31 and 32 is the only groove 95 of the wheel which is firmly in engagement with the work and, consequently, at this stage of the operation a relative slipping movement of the wheel and work is permitted 100 to allow the groove of the wheel to locate itself upon the crown of the stitch.

The wheel 24 is of such small diameter that instead of being mounted to rotate upon a fixed stud as is usual in impression or imitation stitch machines it is preferably provided with a stud 34 projecting from its inner end, which stud is mounted to rotate in a block 35 secured to the upper end of the lever 11. The stud is held from longitudinal movement 105 by means of a transverse pin 36 which engages a groove in the rear end of the stud. On account of the small diameter of the wheel 24 and stud 34 it is preferable that means in addition to the stud be provided 110 for supporting the wheel against the thrust of the work. In the construction illustrated in the drawings these means consists of a guard plate 37 secured to the block 35 and projecting downwardly over the outer end 115 of the indenting wheel. At its lower end and upon its inner surface the guard plate is provided with a recess which receives the outer end of the wheel and with a bearing stud 38 which projects into a hole drilled in 120 the end of the wheel.

To insure the engagement of the teeth of the stitch separating and indenting wheel

with the stitches of the seam the peripheral surface of the wheel upon which the teeth are formed is preferably convexly curved longitudinally of the wheel. The advantages 5 of this construction will be clearly apparent from an inspection of Fig. 4.

In the construction illustrated in the drawings an angular adjustment of the stitch separating and indenting wheel with relation 10 to the work engaging surface of the upper work support is secured by mounting the block 35 in a segmental slot in the upper end of the lever 11, the slot being curved in the arc of a circle, the center of which is at the 15 lower outer edge of the wheel. At the rear of the slot which receives the block 35 the lever 11 is provided with a narrow slot and through this portion of the lever two clamping bolts 39 pass by means of which the block 20 can be secured in any position to which it is adjusted. This angular adjustment of the stitch separating and indenting wheel permits the wheel to be placed in such a position as to act to the best advantage on the 25 stitches of the seam and also adapts the machine for operation upon styles of work which cannot be operated upon satisfactorily by adjusting the lower work support. This adjustment of the stitch separating and indenting wheel also permits a change in the 30 character of the indentations produced by the wheel.

The nature and scope of the present invention having been indicated and a preferred 35 embodiment of the invention having been specifically described, what is claimed is:—

1. A stitch separating and indenting wheel 40 provided with a series of stitch separating and indenting teeth upon its periphery immovable with relation to each other shaped and spaced to permit a relative slipping movement between the wheel and the work to allow each tooth to locate itself in the interval between two stitches whether the 45 stitches are of uniform or varying length.

2. A stitch separating and indenting wheel 50 provided upon its periphery with a series of teeth to indent the stitch intervals and with a series of grooves to shape the crowns of the 55 stitches, the teeth and grooves being shaped and spaced to permit a relative slipping movement between the wheel and the work to allow the teeth to locate themselves in the stitch intervals and the grooves to locate themselves on the crowns of the stitches, whether the stitches are of uniform or varying 60 length.

3. A stitch separating and indenting wheel 65 provided with a peripheral surface convexly curved lengthwise of the wheel, and with a series of teeth projecting from said surface, immovable with relation to each other and shaped and spaced to permit a relative slipping movement between the wheel and work

to allow each tooth to locate itself in the interval between two stitches, whether the 65 stitches are of uniform or varying length.

4. A stitch separating and indenting machine, having, in combination, a lower work support, an upper work support, an indenting tool, and means for adjusting the angular 70 position of the working face of the tool with relation to the work-engaging surface of the upper work support.

5. A stitch separating and indenting wheel 75 provided with a series of stitch separating and indenting teeth upon its periphery immovable with relation to each other, and shaped and spaced to permit a relative slipping movement between the wheel and the 80 work to allow each tooth to locate itself in the interval between two stitches, whether the stitches are of uniform or varying length, a supporting stud for the wheel, and means in addition to said stud for supporting the 85 wheel against the thrust of the work.

6. A stitch separating and indenting wheel 90 provided with a series of stitch separating and indenting teeth upon its periphery immovable with relation to each other, and shaped and spaced to permit a relative slipping movement between the wheel and the work to allow each tooth to locate itself in the interval between two stitches, whether the 95 stitches are of uniform or varying length, and means for supporting the wheel at each end against the thrust of the work.

7. A stitch separating and indenting wheel 100 provided with a series of stitch separating and indenting teeth upon its periphery, immovable with relation to each other, and shaped and spaced to permit a relative slipping movement between the wheel and the work to allow each tooth to locate itself in the interval between two stitches, whether the 105 stitches are of uniform or varying length, a supporting stud for the wheel, and a guard extending over the outer end of the wheel having provision for supporting the wheel against the thrust of the work.

8. A stitch separating and indenting wheel 110 provided with a series of stitch separating and indenting teeth upon its periphery immovable with relation to each other, and shaped and spaced to permit a relative slipping movement between the wheel and the work to allow each tooth to locate itself in the interval between two stitches, whether the 115 stitches are of uniform or varying length, a supporting stud rigid with the wheel and projected from its inner end, and means in addition to the stud for supporting the wheel against the thrust of the work.

9. A stitch separating and indenting wheel 120 provided with a series of stitch separating 125 and indenting teeth upon its periphery immovable with relation to each other, and shaped and spaced to permit a relative slip-

ping movement between the wheel and the work to allow each tooth to locate itself in the interval between two stitches, whether the stitches are of uniform or varying length, 5 a supporting stud integral with the wheel and projecting from its inner end, and a guard extending over the outer end of the wheel provided with a stud for supporting the outer

end of the wheel against the thrust of the work.

In testimony whereof I affix my signature. 10 in presence of two witnesses.

JOHN B. HADAWAY.
